UNITED STATES PATENT OFFICE.

JOHN H. GLASMANN, OF DENVER, COLORADO, ASSIGNOR TO JAMES E. SNELL,
OF SAME PLACE.

FOLDING CAMP-STOVE.

SPECIFICATION forming part of Letters Patent No. 497,275, dated May 9, 1893.

Application filed April 16, 1892. Serial No. 429,499. (No model.)

To all whom it may concern:

Be it known that I, JOHN H. GLASMANN, a citizen of the United States of America, residing at Denver, in the county of Arapahoe and 5 State of Colorado, have invented certain new and useful Improvements in Folding Camp-Stoves; and I do declare the following to be a full, clear, and exact description of the invention, such as will enable others skilled in 10 the art to which it appertains to make and use the same, reference being had to the accompanying drawings, and to the figures of reference marked thereon, which form a part of 15 this specification.

15 My invention relates to improvements in camp stoves and the object of the invention is to provide a stove of the class stated which may be quickly and easily folded up into very 20 small compass for convenience of transportation from place to place or for storage when not in use.

To these ends the invention consists of the 25 features, arrangements and combinations hereinafter described and claimed, and which will be fully understood by reference to the accompanying drawings, in which is illustrated an embodiment thereof.

In the drawings, Figure 1 is a perspective 30 view of my improved stove ready for use. Fig. 2 is a similar view of the rear side of the same, partly upraised to show the bottom. Fig. 3 is a perspective view of the removable oven. Fig. 4 is a perspective view in detail showing the manner of joining the bottom and sides of 35 the stove when in use. Fig. 5 is a top or plan view of the stove with the top removed. Fig. 6 is a side view with one side removed. Fig. 7 is a perspective view showing the stove partly folded. Fig. 8 is a perspective of a section of the pipe employed. Fig. 9 is a sectional detail illustrating the manner of attaching the pipe to the top of the stove.

Similar reference characters indicating corresponding parts or elements of the mechanism in the several views let the numeral 5 designate the front side of the stove which is preferably composed of sheet iron. The front side of the stove is provided with a door 6 leading to the fire box, and another door 7 affording access to the oven 8. To the upper

side of the front 5 is hinged the top 9 as shown at 10. This top is provided with a depending flange 12 formed on its rear side edge and overlapping the upper edge of the rear side 13. This flange is provided with hooks 14, 55 adapted to engage catches or eyes 15 formed on side 13 and occupying a position in proximity to the hooks when the stove is in use. The top 9 is also provided with depending end flanges 16 which overlap the upper edges of 60 the folding ends 17. These ends are each composed of two twin sections hinged together at 18 and to the vertical side edges as shown at 19.

The bottom 20 is hinged to the lower horizontal side edge 21 of the rear side 13. This bottom occupies a position between the sides and ends of the stove and is provided with depending flanges 22 formed on its ends and free side to engage correspondingly 70 projecting flanges 23 formed on the lower horizontal edges of the two ends and one side. When the stove is in position for use this bottom braces the side walls of the stove from the inside. This bottom is held in position 75 when the stove is in use by transverse slides 24 which engage the bottom flanges 25 and overlap the lower horizontal edges of the vertical sides, thus locking the bottom in place. These slides, 24, as shown in the drawings, are 80 formed concavo-convex with their convex surfaces extended downwardly. The depending parts of these slides may be made of any sufficient length to form legs for supporting the stove at any desired distance from the ground 85 or surface upon which the stove rests.

The stove is provided with a removable oven 8 composed of the top 2, bottom 3, and two sides 4 hinged together as shown at 8^a and adapted to fold or close up when not in 90 use. This oven is provided with vertical flanges 8^c adapted to engage corresponding flanges 26 formed on the sides of the stove.

To the top of the oven is hinged a damper 27, which when raised engages the top of the 95 stove and occupies a position between the fire box and the rear opening through which the smoke escapes. This damper is controlled by a wire or small rod 28 which projects through a suitable aperture formed in the 100

rear end of the stove through which it is passed when the oven is put in place. This oven is open at the sides adjacent the front and rear sides 5 and 13 of the stove body and may be 5 folded up when not in use.

As shown in the drawings the top of the stove is provided with three openings 30, 30, and 31. These openings 30 are provided with suitable covers 32 which may be hinged to the 10 top as shown in Fig. 1. Opening 31 is the smoke exit and is partly surrounded by flanges 33 (Fig. 9) which are engaged by corresponding flanges 34 formed on the lower horizontal edge of the pipe 35 which is rectangular 15 angular in cross section and composed of four parts having their vertical edges hinged together as shown at 36.

When not in use, the pipe is first removed and folded, the top unhooked and raised and 20 the oven removed and folded by virtue of the construction heretofore described. The slides 24 are then removed, releasing the bottom, which is folded up against side 13 as shown in Fig. 7. The front and rear sides are then 25 made to approach each other by folding the ends inward as shown in Fig. 7. The folded oven and pipe are then dropped in between the folding sides which are then pressed together, the entire stove being formed into a 30 neat, symmetrical package, requiring very little space for storage or transportation. It is preferably packed within a suitable box constructed for the purpose. A stove one foot in width of my improved construction may be 35 folded into a space about two inches in width, thus greatly reducing the bulk of the article.

The operation of putting up the stove is just the reverse of taking it down or folding it up, and either act may be accomplished in 40 a few minutes.

The top of the stove is provided on the under surface with depending lugs or projections A, adapted to engage and brace the ends and front side outwardly and so lock them 45 when in use as to prevent the possibility of their folding inward.

Having thus described my invention, what I claim is—

1. As an improved article of manufacture 50 a folding camp stove having hinged vertical sides, a top hinged to one side and attached to the opposite side by hooks engaging suitable catches, and a bottom hinged to one vertical side of the stove body and provided with 55 depending flanges formed on its three edges and adapted to engage counterpart upwardly

turned flanges formed on the lower horizontal edges of the vertical sides, substantially as described.

2. As an improved article of manufacture 60 a folding camp stove having hinged vertical sides, a top hinged to one of these sides and detachably connected with the other side; a bottom also hinged to one side and having depending hooked flanges on its free edges 65 engaging counter-part upwardly turned flanges formed on the vertical sides, and a locking slide engaging exterior ways formed on the bottom, said slide overlapping two of the side edges, substantially as described. 70

3. As an improved article of manufacture 75 a folding camp stove having hinged vertical sides, a top hinged to one of these sides and detachably connected to the other side, a bottom also hinged to one side and having depending hooked flanges on one or more of its 80 free edges engaging counter-part upwardly turned flanges formed on the vertical sides, and slides, the edges of which engage exterior ways formed on the bottom and overlapping the side edges whereby the bottom is 85 locked in place, said slides being bent outwardly from the bottom to form a support for the stove during use, substantially as described. 95

4. As an improved article of manufacture, 90 a camp stove having its outer body part composed of hinged sections adapted to fold up, and a removable oven located within the body part and provided with vertical flanges adapted to engage counter part ways formed on two opposite sides of the oven and attached to the stove body, the oven being composed of hinged parts and adapted to fold up, substantially as described. 95

5. As an improved article of manufacture 100 a camp stove having its outer body part composed of hinged sections adapted to fold up and a removable oven located within the enclosure of the stove body and provided with vertical flanges adapted to engage ways formed on the stove body, the oven being composed 105 of hinged parts, and a damper hinged to the top of the oven and adapted to engage the top of the stove body above the oven, substantially as described.

In testimony whereof I affix my signature in presence of two witnesses.

JOHN H. GLASMANN.
